BEVERAGE DISPENSING DEVICE

Bruce G. Copping, Fulton County, Ga., assignor
to The Coca-Cola Company, Wilmington, Del.,
a corporation of Delaware

Application December 9, 1943, Serial No. 513,577

6 Claims. (Cl. 222—145)

1

This invention relates to dispensing devices, and more particularly to a new and improved automatic valve for dispensing carbonated water together with a fixed quantity of syrup, in conjunction with a new grooved-type capillary nozzle; the composite device having preferred use at soda fountains and the like in the merchandising of soft drinks.

It has long been a problem to consistently dispense an exact quantity of beverage syrup, along with highly carbonated water which increases the potability of the finished drink. In addition, devices of this general type present problems in sanitation, since the cleaning thereof is often difficult. The present invention is concerned with the solution of these and other problems.

An object of the instant invention is to provide an automatic valve which is simple and accurate in its operation and construction.

Another object is to provide a no-drip feature in a dispenser, whereby the flow of all syrup instantly ceases when the device is cut off.

Another object is to provide straight-through flow in such an instrumentality.

Another object is to provide ease of access in a dispenser whereby the entire syrup system is readily exposed for cleaning purposes.

Another object is to provide improved mix of syrup and carbonated water in a dispenser.

A still further object is to provide high carbonation in such a device.

Another object is to provide cheapness of construction.

Another object is to make possible mass production of beverage dispensers.

These and other objects are accomplished by means of the instant invention, a full and complete understanding of which is facilitated by reference to the drawings herein, in which:

Fig. 1 is substantially a vertical sectional view of the dispenser, taken through the approximate center thereof.

Fig. 2 is a slightly enlarged horizontal sectional view taken along the line 2—2 of Fig. 1;

Fig. 3 is an enlarged horizontal sectional view taken along the line 3—3 of Fig. 1;

Fig. 4 is an enlarged side-elevational view of a portion of the improved nozzle member employed;

Fig. 5 is a greatly enlarged fragmentary top view of the center portion of said nozzle member, showing one of the V-shaped grooves therein; and

Fig. 6 is an enlarged fragmentary view illustrating a modification of said nozzle.

Referring now to the drawings, it will be noted

2

that the dispenser consists of two main parts, to-wit, the carbonated water dispensing system; and the system for measuring and dispensing a fixed quantity of syrup.

5 A main valve body 10 may be supported within a metallic shell 11 insulated as at 12; in conjunction with a syrup tank 13, as is described in detail hereinafter. Carbonated water is supplied to the valve through the inlet passage 14, and thence enters the valve through the valve seat insert 15, the flow of carbonated water entering the valve being controlled by the valve 16, in which are set rubber valve disks 17. The valve 16 and said rubber disks are held upward to close the valve insert 15 by means of push rods 18, which are, in turn, pressed upward by the flange 19 on the outer sleeve 20, which is normally held in the full-up position by a spring 21 acting on nut 22.

Inside the outer sleeve 20 is a syrup tube 23, 20 which tube is free to slide within said outer sleeve, and is normally held in an upward position by the spring 24 acting on the syrup tube nut 25.

A rubber diaphragm 26 seals between the syrup tube 23 and the main body 10 of the valve, thus 25 preventing the escape of any syrup at this point. Said diaphragm is, however, sufficiently flexible to permit the free vertical motion of the syrup tube 23. On the lower end of the syrup tube is attached a nozzle assembly 27.

30 28 is a syrup valve assembly which consists of the flow shut-off valve 29 connected to 28 by rod 29a, the supply shut-off valve 30, the air-check valve 31, the air-vent tube 32, and a lifting handle 33. This valve is so arranged relative to the 35 syrup tube 23 and the supply valve seat 30 that when the syrup tube is in the full upward or closed position, the flow shut-off valve 29 seats at 34 at the top of syrup nozzle 35, while the supply shut-off valve 30 is raised an appreciable distance off the supply valve seat 30.

37 is a cylindrically shaped straining element, the diameter of this element and the syrup valve assembly 28 being such as to maintain a fairly close clearance between these two elements, notwithstanding which it will be seen that by lifting upwardly on the handle 33 the entire syrup valve assembly may be removed from the unit so as to permit complete and easy washing of these parts, and of the valve through which syrup 45 passes.

The main support sleeve 38 is permanently cast into main body 10, and provides a support within which outer sleeve 20 and the syrup tube 23 are free to slide.

55 Mounted on the outside of support sleeve 38 is

the grooved-type capillary nozzle 39, special attention now being directed thereto:

Element 40 is a plug preferably of cylindrical contour, upon the surface of which has been cut a plurality of longitudinal grooves 41 (see Figs. 4 and 5), which grooves are of such cross-sectional dimensions and lengths as to conform with the theory of viscous flow as described and set forth at length in my co-pending patent application, Serial No. 480,108, Automatic valve for dispensing and proportioning syrups and carbonated water, filed March 22, 1943, of which the present case is a continuation in part. 42 is a cylindrical sleeve, which is shrunk fit upon cylindrical plug 40. The lower end of said plug is tapered off to a smaller diameter as at 43, and the lower inside face of sleeve 42 is tapered outwardly as at 44, with the result that when the parts are in position, an annular space 45 is formed at the discharge end of grooves 41, which annular space has a gradually enlarging cross-section. 46 is a wire screen of reasonably fine mesh, which is held across the lower end of annular space 45 by shoulder 47 of ring piece 48 bearing on retaining ring-washer 49, which screws into outer sleeve 50; said sleeve, in turn, engaging the main body portion 10 of the valve, in a similar manner.

From Fig. 3 it will be apparent that when sleeve 42 is shrunk onto plug 40, the inner face of the sleeve closes off the open side of the grooves 41, and, in effect, creates a number of passages running longitudinally through the nozzle, said passages in the form shown having approximately a triangular section, although this is not essential to the invention, it being apparent that said grooves may have a rectangular cross-section, a square cross-section, or a semi-circular cross-section, or, in fact, any desired shape, although the V contour is deemed preferable because it gives a very excellent hydraulic radius, and because it is a practical shape to manufacture.

At this point it may be in order to consider at some length the basic theories underlying the design of the instant nozzle. In handling carbonated water it is not only helpful to cause the stream of liquid passing from a storage container into an instrumentality such as a glass which is open to the atmosphere, to flow through a conduit which is so designed that turbulence is reduced to a minimum; but it is also desirable to so conduct the liquid to the point of discharge in such a manner that there is a gradual, instead of a sudden pressure drop, there being a minimum separation of carbonic acid gas out of the liquid when such is discharged at relatively low velocity and pressure. The grooved-type capillary nozzle herein is designed with these considerations in mind, delivering a stream of carbonated water into a container at atmospheric pressure, in a highly desirable manner, a gradual pressure drop being effected and high carbonation maintained for this reason, and a non-turbulent flow being likewise achieved, the net result being delivery of carbonated water under the most optimum conditions.

In this connection, it will be noted that the large number of V-shaped grooves in nozzle element 40 are relied upon to absorb the pressure energy of the carbonated water as it flows through the nozzle, without causing it to depart from streamline flow and become turbulent, the effect being such that the carbonated water is delivered at the lower end of the energy-absorb-

ing at very low pressure, and with retardation of velocity effected by means of screen 46 co-operating with opening 45, the water runs downwardly to mix with syrup issuing from element 35 under conditions which guarantee maximum potability of the finished drink.

It is apparent that various structures may be employed for achieving the relatively slow uniform pressure drop in the carbonated liquid as it approaches the mouth of the discharge nozzle, while maintaining streamline flow. For a dispenser of the instant type, the pressure reducing means illustrated has been found practical, being of simple design and easily cleaned.

It will be understood that in the design of the pressure-reducing means the character of the liquid which is to be dispensed must be given full consideration, with particular reference to its absolute viscosity and density.

It is known for example that the absolute viscosity and density of a liquid to be handled should be known in order to determine the maximum velocity of flow which may be permitted to occur while maintaining streamline flow, i. e., without causing turbulence or transverse movements of the particles of flowing liquid. As previously stated, the flow of carbonated water from a tank to a receiving vessel should be streamline or non-turbulent if the loss of absorbed gas is to be minimized. Hence, as a primary consideration in the design of a pressure reducing means which comes within the import of the present invention it is first desirable to consider the nature of the liquid to be dispensed and to obtain some idea of the maximum permissible velocity of flow of that liquid which may be permitted without causing turbulence.

For any given liquid, under any given conditions, there exists a critical velocity the value of which depends upon the ratio of the inertia forces involved to the viscous forces. One method of determining the critical velocity of a given liquid flowing through a pipe or conduit involves the computation of what is called the Reynolds number for that liquid, the Reynolds number of the liquid determined from the following equation:

$$Re = \frac{\text{Pipe diameter} \times \text{fluid velocity}}{\text{kinematic viscosity}}$$

50 or

$$Re = \frac{D \cdot V}{u/p}$$

55 where

D=pipe diameter

V=fluid velocity

u=absolute viscosity

p=density of liquid

60 when the Reynolds number exceeds an upper critical value of from 1500 to 3000 turbulent flow occurs, whereas, when the Reynolds number is below this critical value streamline flow occurs.

With the knowledge in mind that the Reynolds number may not be exceeded if streamline flow is to be maintained, and that the diameter of the pipe through which the liquid flows, as well as the absolute velocity and density of the liquid are factors in the Reynolds number formula, the 65 design of a specific means for effecting the necessary pressure drop in the flowing liquid can be undertaken with the aid of further formulae of proven value heretofore used in the design of conduits utilized for the transmission of flowing liquids.

It has been previously said that the carbonated liquid must be stored under considerable pressure. In this state, the liquid has potential, or "stored-up," energy by virtue of its pressure. Before the drink can come to rest in a glass or cup, this energy must be used up. One way of using up this potential energy, which is now almost universally used, is to allow the liquid to squirt out through a small nozzle. In this case, the potential energy is immediately converted into kinetic, or "velocity," energy, and causes the liquid to come rushing out at velocity far above the "critical" velocity for streamlike flow. The turbulent stream of liquid thus created hits violently into the glass, and the "velocity" energy is eventually turned into heat in the liquid through the violent turbulence of the liquid in the glass.

There is another way in which the potential, or "stored-up" energy of the liquid may be used up. That is by arranging to have the potential energy used up by the friction created during the flow of the liquid through the dispensing system. It is possible to use up virtually all of the energy of the liquid in friction, so that the liquid issues from the discharge end of the nozzle at atmospheric pressure, and virtually no velocity, and the present invention contemplates the utilization of a friction means for accomplishing this objective. In the design of such a means to act upon a selected liquid, which shall be capable of practical use, it is desirable to first consider the Reynolds number equation above set forth.

The kinematic viscosity is constant for a given liquid at fixed temperature, so that the Reynolds number varies as the product of the pipe diameter and the velocity. The significant feature of this is that, by making the pipe very small, we can make the velocity very high and still have the same Reynolds number, i. e., less than 3000, and maintain streamline flow.

The commonly used equation for flow of liquids in pipes is as follows:

$$h_f = f \cdot \left(\frac{L}{D} \right) \cdot \left(\frac{V^2}{2g} \right)$$

where:

h_f =loss of pressure due to friction

f =a coefficient depending on Reynolds number

L =length of the pipe

D =diameter of pipe

V =velocity of flow

g =acceleration due to gravity

An examination of this formula shows that the loss of pressure due to friction in the pipe increases as the square of the velocity and inversely as the diameter of the pipe. Thus, if the pipe is made $\frac{1}{10}$ as large and the velocity increased ten times (as may be done without causing turbulent flow), the length of pipe needed to use up the pressure in the liquid under these conditions will only be $\frac{1}{100}$ of what it was before. It is naturally necessary to increase the number of pipes as they are made smaller, in order to carry the same quantity of liquid. This increase must be in inverse proportion to the change in diameter. That is, if it is decided to reduce the diameter to $\frac{1}{10}$, and increase the velocity ten times, as above, then ten of the small pipes will be needed to carry the same quantity of liquid per second as the original pipe.

The important characteristic of a small tube, which governs the friction loss in that tube, is the ratio:

$$\frac{\text{Cross section area}}{\text{Wetted perimeter}}$$

in other words, the ratio of the frictional surface to the thickness of the stream. This ratio is known as the "hydraulic radius."

The significant point to note, in this connection is that all fluid ducts, of whatever cross sectional shape, will behave the same as regards friction loss, provided that they have the same "hydraulic radius." If it be assumed that "N" small tubes must be utilized in the construction of a nozzle of the type contemplated and that each has a diameter, inside, of D inches, the hydraulic radius of each tube is then:

$$= \frac{X - \text{section area}}{\text{Wetted perimeter}}$$

$$= \frac{\pi D^2}{4} = \frac{D}{4}$$

The total area of all the tubes together is:

$$N \times \text{area of each} = \frac{N \cdot \pi D^2}{4}$$

What is desired, therefore, is a duct of some sort, so shaped that its hydraulic radius

$$= \frac{D}{4}$$

and of such size that the X -section area

$$= \frac{N \cdot \pi D^2}{4}$$

35 The shape selected must also be easily cleaned.

At this point it may be in order to consider certain sample calculations showing how the theory of streamline flow may be applied to the actual design of a V-groove type capillary nozzle.

40 As an example, let it be assumed that it is desired to design a nozzle for dispensing carbonated water. The conditions to be met are as follows:

(a) Required rate of discharge=1 fl. oz. in 5 secs.

$= .001066 \text{ cu. ft./sec.}$

45 (b) Required pressure drop thru nozzle=100 lbs.

$= 231 \text{ ft. of water}$

(c) Required length of capillaries=.145 ft.

(d) Temperature of water= 40° F.

(e) Viscosity of water=.00104 lbs./sec. ft.

(f) Density of water=62.45 lbs./cu. ft.

50 It is required to determine the size, and number of passages required to dispense carbonated water, at the above rate, under the above conditions, and maintain streamline flow throughout.

To simplify calculations it is assumed first that the capillary passages will have a circular cross-section and the diameter of such passages is determined. The size of an equivalent passage of triangular section is then worked out.

60

Reynolds number

The criterion used in determining whether or not streamline flow prevails is the Reynolds number.

65

$$\text{Reynolds No.} = \frac{DVP}{\mu}$$

where:

D =diameter of passage

V =velocity of flow

P =density of liquid

μ =viscosity of liquid

When the Reynolds number is below a value of about 1500 complete streamline flow will prevail.

75 A value of between 1500 and 3000 indi-

7
cates that the flow is in a "critical" range where the flow is partially streamline and partially turbulent. Over 3000 indicates completely turbulent flow. The selection of the Reynolds number fixes the relationship between the diameter of the passage (d) and the velocity of flow (V) as follows:

Value of $D \times V$

$$\text{Reynolds No.} = \frac{D V P}{\mu}$$

$$\therefore 1500 = \frac{D V \times 62.44}{.00104}$$

$$\therefore D V = \frac{1500 \times .00104}{62.43} = .02497$$

$$\therefore D = \frac{.02497}{V} \quad (1)$$

To find D and V

The basic formula for the flow of fluids thru closed passages is:

$$h_f = \frac{f L V^2}{D^2 g} \quad (2)$$

where:

h_f = loss of head (in feet of water)

L = length of passage

V = velocity of flow

D = diameter of passage

g = acceleration due to gravity

f = a factor depending upon the Reynolds No.

For streamline flow

$$f = \frac{64}{\text{Reynolds No.}} = \frac{64}{1500} = .0427$$

Substitute in Equation 2 the various values heretofore indicated:

$$231 = \frac{.0427 \times .145 \times V^2}{\frac{.02497}{V} \times 2g}$$

$$= \frac{.0427 \times .145 \times V^3}{.02497 \times 64.4}$$

$$\therefore V^3 = \frac{231 \times .02497 \times 64.4}{.0427 \times .145}$$

$$V^3 = 60100$$

$$V = \underline{\underline{39.2 f/s}}$$

From Equation 1:

$$D = \frac{12 \times .02497}{39.2} = .00764 \text{ inch}$$

Because for practical reasons the largest possible passages commensurate with streamline flow are desired the value 1500 is selected for the Reynolds number.

There has been thus established the diameter of a cylindrical passage to fulfill the specified condition. It remains to be determined, first, the size of an equivalent "V-groove," and, second, the number of such grooves required to provide the specified rate of discharge.

Equivalent V-groove

Here is selected as the cross-sectional shape of the V-groove a 60° groove, which when closed on the open side will approximate an equilateral triangle as shown in Fig. 5. Let the side of this triangle be a and its altitude h . An "equivalent" V-groove will be one whose hydraulic radius equals that of a cylindrical passage of diameter $D = .00764$ inch (as determined above).

Hydraulic radius = $\frac{\text{area}}{\text{perimeter}}$

∴ For circular section hyd. rad. = $\frac{D}{4}$

∴ For triangular section hyd. rad. = $\frac{.43301a^2}{3a}$
= $.1443a$

10. ∴ For equivalent "V-groove"

$.1443a = \frac{D}{4}$

15. $\therefore a = \frac{.00764}{4 \times .1443} = .01324 \text{ inch}$

$h = a \sin 60^\circ = .01324 \times .866 = .01146 \text{ inch}$

No. of passages required

20. The velocity of flow at 39.2 feet/sec. has been determined. There is required a total discharge of .001066 cubic ft./sec. The combined cross-section area of all grooves required will therefore be:

25. $\frac{.001066}{39.2} = .0000272 \text{ sq. ft.}$

Cross-section area of one V-groove of side a

30. $= \frac{.43301 \times a^2}{144}$

∴ Cross-section area of 1 V-groove

35. $= \frac{.43301 \times .01324^2}{144}$
= $.000000527 \text{ sq. ft.}$

∴ To find the total number of grooves required it is only necessary to divide the total area required by the cross-section area of a single groove, thus:

40. Number of grooves required = $\frac{.0000272}{.000000527} = 51.6$

The nearest full number — 52 is accordingly selected.

Thus to fulfill all the conditions set forth above, the capillary passages will be as follows:

Length of passages = .145 ft.

Number of passages = 52

Altitude of "V-groove" = .01146 inch

Side length of "V-groove" = .01324 inch

55. In Fig. 6 is shown a somewhat similar arrangement to that previously described except that the grooves 41 have been placed on the inside face of the sleeve 42, rather than on the outside of plug 40, there being no essential difference in principle of operation between the two arrangements shown, but certain manufacturing considerations possibly suggesting a use of one construction under some circumstances, and another under different conditions.

60. Gaskets 51 help to seal the grooved capillary nozzle assembly in place, and prevent leakage of liquid at this point, and bushings 52 and 53 are provided in the shell in which the valve is mounted. A locking ring 54 which screws onto the outside of 50 and bears against 53 which has theretofore been screwed onto 52, is used to fasten 65. the valve assembly in place within said bushings. A non-metallic bushing 55 forms a firm seal between the bushings when 53 is tightened, and a rubber gasket 56 prevents the leakage of water from the water bath in which the valve may be 70. surrounded, as for cooling purposes.

The nozzle assembly 27 is preferably provided with curved vanes 57, and inward curving outer ring 58 is so designed as to project an inward turning, whirling stream of carbonated water against the syrup stream issuing from nozzle-piece 35, thus facilitating an adequate and proper mixing of syrup and water.

In order that the flow of syrup from the syrup chamber 59 may take place, it is necessary to provide a means of entry for air to replace syrup, and this is accomplished by means of air-vent tube 32 and rubber check-valve 31, the latter being made of very soft and flexible rubber, and so designed that a very slight downward suction in the syrup chamber 59 will create a flow of air downward through the check-valve into the tank. The purpose of the check-valve itself is to prevent syrup from backing up into the air-vent tube during the operation of filling chamber 59, and the reason for wishing to prevent this is that there would otherwise occur a small error in the amount of syrup discharged, depending upon the level of syrup in tank 13. For example, if the tank were virtually empty, then the syrup would only back up into tube 32 in small quantity, and this would be discharged when the valve became operative, but, on the other hand, if the tank were practically full, then during the filling operation syrup would back up into the air-vent tube to the level of syrup in said tank, under which circumstances the amount of syrup discharged would be appreciably greater than when the lower level of fluid prevailed. This arrangement permits of great accuracy in measuring the quantity of syrup to be dispensed under varying conditions.

The operation of the instant dispenser is as follows:

When the valve is in disuse and no flow is occurring, springs 21 and 24 force the syrup tube 23 and the outer-sleeve 20 to their full upward position, and because said syrup tube is in such position, the flow shut-off valve 29 is seated on the upper end 34 of syrup nozzle 35 thereby shutting off any possible flow of syrup through this tube. Both a positive valve action, and, due to the relatively small diameter of the tube, a utilization of principles of physics inherent in a pipette, are thus employed in guaranteeing that not the slightest drop of syrup will escape under these conditions. This is obviously desirable from a sanitary standpoint, as escaping syrup attracts flies and other undesirable insects and vermin.

The whole valve assembly 28 is also raised so that the supply shut-off valve 30 is clear of its seat 36, and syrup is now free to enter the syrup chamber 59, the air then displaced from said chamber escaping upwardly through the syrup into tank 13. The rubber check-valve 31 prevents the entry of syrup into the vent tube 32, as has been described heretofore. With the valve in the closed position the upward pressure of the spring 21 forces outer-sleeve 20 to the full-up position and through the flange 19 and push-rods 18, forces shut-off valve 16 and the rubber valve-disks 17 against valve seat bushing 15, thus preventing any flow of carbonated water. Valve insert 68 is merely a dummy, provided to prevent unbalanced forces on the valve 15.

When it is required to operate the dispenser, downward pressure is applied to the operating lugs 61, which pressure is transmitted to the syrup tube 23, which is thereby drawn downward. During the first part of this motion the outer-sleeve 20 does not move. The downward

motion of syrup tube 23 first permits the supply shut-off valve 30 to reach its seat 36 and shut off the supply of syrup; and then begins to draw away from the flow shut-off valve 29. At this point, the lower extension of the syrup tube nut 25 contacts the upper end of the outer-sleeve 20 and begins to force it downwardly, which motion releases the upward pressure of rods 18 against valve 15 and thus permits the carbonated water valve to open. It will be seen that through this mechanism there is provided a simultaneous opening of the syrup valve 29 and the carbonated water valve 15, which is important because it makes it impossible for the operator to draw either carbonated water or syrup alone from the valve at this time, the valve only dispensing the two ingredients together. When the carbonated water valve 15 is open the full carbonated water pressure is applied to the upper end of the grooved capillary nozzle assembly, and the carbonated water flows downwardly through the V-shaped capillaries, at such a rate as to fulfill the two basic requirements of the capillary nozzle, to-wit, that all or substantially all of the potential energy of the liquid be used up by friction and that streamline flow be maintained throughout.

Because these passages are appreciably larger in size than the .002 of an inch passages described in my said pending application, Serial No. 480,108, the exit velocity of the liquid is higher, and it becomes necessary by some means to destroy or nullify such velocity in order that the carbonated water leaving the nozzle may not churn up the liquid in the receptacle into which it discharges, too violently. It is for this purpose that the gradually enlarged annular space 45 is provided, and as the water discharges from the lower end of the V-shaped grooves 41 it enters this space, whereupon fine screen wire 46 offers sufficient retarding effect to the stream so that the annular space 45 readily becomes filled with liquid. When this condition obtains there is produced a Venturi effect, in which the velocity of the liquid is reduced in direct proportion to the enlargement of the space. Thus, by the time the liquid reaches the large end of 45, it is flowing at low velocity, and is in suitable condition for entering a container without undue agitation.

By way of example, but not of limitation, it may be noted that in the present nozzle grooves have been used, the depth of which from the center of the base to the peak is .011 of an inch, this representing an opening almost six times as great as in the case of the initial capillary nozzle described in my said patent application; advantages in manufacture and cleaning the present arrangement being readily apparent.

As the highly carbonated water passes through screen 46 it encounters the inwardly curved surface of outer ring 48 and likewise impacts against curved vanes 57, whereby an inwardly turned, whirling stream of water merges with the syrup stream issuing from nozzle 35, the result being a thoroughly mixed, highly carbonated and delicious finished drink.

Upon release of pressure on the operating lugs 61, the device automatically returns to closed position, valve 16 seating against 15 and stopping the flow of carbonated water; valve 29 seating at 34 and stopping the flow of carbonated water; valve 29 seating at 34 and stopping all flow of syrup through nozzle 35; and valve 30 unseating at 36 in order that syrup chamber 59 may immediately fill in anticipation of another dispensing operation.

An important feature of the instant invention is the ease with which the syrup system may be drained and cleaned, it being a common failing of dispensing valves that syrup measuring elements are frequently sealed up and inaccessible, or otherwise not readily cleanable. When it is desirable to wash out the syrup system of the instant valve, it is only necessary to lift out the entire syrup valve assembly 28 by lifting upwardly on the handle 33, which handle is preferably above the level of the syrup in tank 13. When the syrup valve assembly has been withdrawn, whatever syrup remains in the tank and the syrup chamber is run out through syrup tube 23 and nozzle 35, and may be caught in a suitable container. When drainage is complete, the entire syrup system, including the tank 13, the syrup chamber 59, the syrup tube 23, and the syrup nozzle 35 may be thoroughly cleaned and washed, all of these parts being open to visual inspection during such procedure.

The structure shown is simple and economical to manufacture, all major parts being cylindrical and susceptible of screw machine production, which suggests the practicability of making these dispensers on a large scale.

From the foregoing it will be apparent that there has been described a new and improved device of the instant type capable of dispensing a highly carbonated, thoroughly mixed, quality drink. That no syrup can escape from the syrup nozzle between operations; that the entire assembly is readily cleaned; and that simplicity of operation and economy of manufacture are inherent in the device.

While there has been described herein a preferred embodiment of the instant invention, and a modification of the new grooved-type capillary nozzle, it will be understood that no limitation is implied thereby, but on the contrary, appropriate modifications, rearrangements, reconstructions, changes and the like may be resorted to without departing from the scope of the appended claims, which are to be accorded a construction fairly in keeping with the contribution to the art.

Having thus described the invention, what is claimed as new and desired to be secured by Letters Patent is:

1. In a device of the character described, a syrup tank, a syrup measuring chamber positioned therein, filtering means between the tank and chamber, a valve regulating the entrance of syrup into the chamber, a check-valve in said chamber, a syrup tube communicating with the chamber, a syrup nozzle on the end of said tube, a flow regulating valve in said tube, spring means normally retaining said valve in a closed position concurrently with the valve between the chamber and tank being in an open position, a carbonated water inlet, a valve governing said inlet, spring means normally holding said valve in a closed position, means forming V-shaped apertures of such length, size and hydraulic radius as to use up substantially all of the pressure energy of the fluid, in friction, and at the same time maintain streamline flow in the fluid, disposed adjacent said carbonated water inlet, fluid velocity reducing means adjacent the discharge ends of said apertures, a nozzle adjacent said restricting means having an inwardly-turned surface and, vanes in said nozzle, whereby a stream of carbonated water is given a whirling motion and directed towards syrup issuing from the syrup nozzle.

2. In a device of the character described, a

75

syrup tank, a syrup measuring chamber adjacent thereto, a valve between said tank and chamber, a syrup tube communicating with said chamber, a syrup nozzle on the end of said tube, a valve in said tube, means co-ordinating said valve with said first-mentioned valve whereby same is opened only when said first-mentioned valve is closed; a carbonated water inlet, valve means governing said inlet and being co-ordinated with the valve in said syrup tube so as to open simultaneously therewith, means forming V-shaped apertures of such length, size and hydraulic radius as to use up substantially all of the pressure energy of the fluid, in friction, and at the same time maintain streamline flow in the fluid, disposed adjacent said carbonated water inlet, fluid velocity reducing means adjacent the discharge ends of said apertures, nozzle means operatively positioned with reference to said discharge ends, and vanes in said nozzle for the purpose of imparting a whirling motion to fluid issuing therefrom and directing such against a column of syrup simultaneously issuing from the syrup nozzle.

25. 3. In a device of the character described, a syrup tank, a syrup measuring chamber adjacent thereto, and a removable syrup valve assembly disposed in the tank, said assembly including a check-valve communicating with said chamber and permitting air to replace syrup during a withdrawing operation, valve means between the chamber and tank governing the flow of syrup into the chamber; a discharge tube communicating with said chamber, valve means in said tube governing the flow of syrup therethrough, and handle means adjacent the top of said chamber for removing the syrup valve assembly.

4. In a device of the character described, a carbonated water inlet, and a capillary nozzle communicating therewith, said nozzle comprising an interior plug, a plurality of longitudinal grooves therein, said grooves being of such length, size and hydraulic radius as to use up substantially all of the pressure energy of the fluid, in friction, and at the same time maintain streamline flow in the fluid, a sleeve surrounding the exterior surface of said plug, an enlarged annular space formed in said sleeve and plug adjacent the discharge ends of said grooves, and fluid velocity retarding means disposed across the discharge end of said annular space.

5. In a beverage dispenser, a syrup tank, a syrup measuring chamber adjacent thereto, and a removable syrup valve assembly disposed in the tank, said assembly including valve means between the chamber and the tank governing the flow of syrup into the chamber, discharge means in said chamber, valve means governing the flow of syrup therethrough, and means adjacent the top of said chamber for removing the syrup valve assembly from the tank.

6. In a beverage dispenser, a syrup tank, a syrup measuring chamber adjacent thereto, and a removable syrup valve assembly disposed in the tank and chamber, said assembly including valve means governing the entrance of syrup into the chamber, means for discharging syrup from said chamber, and a valve governing said last mentioned means, said valve only being allowed to open when the initial syrup controlling valve is closed; and means adjacent the top of said chamber for removing the syrup valve assembly from the dispenser.
